Geo. A. Hutchinson

Attorney

UNITED STATES PATENT OFFICE.

GERTRUDE G. SCOTT, OF WELDON, NORTH CAROLINA.

LUGGAGE-CARRIER.

1,249,522.

Specification of Letters Patent. Patented Dec. 11, 1917.

Application filed August 13, 1917. Serial No. 185,886.

To all whom it may concern:

Be it known that I, GERTRUDE G. SCOTT, a citizen of the United States, residing at Weldon, in the county of Halifax and State of North Carolina, have invented certain new and useful Improvements in Luggage-Carriers, of which the following is a full, clear, and exact specification.

This invention relates to luggage carriers for automobiles, and has for its object to provide a simple and inexpensive device of this kind which may be readily attached to the running board of any automobile.

A special object is to provide improved means of adjustment, whereby the carrier may be easily arranged to hold boxes or packages of different sizes with equal security, and the members of the carrier are positively held in adjusted position as long as said carrier is attached to the running board of the car, and are locked more securely in that position by the means which fastens the carrier to the running board.

The invention will be first hereinafter described in connection with the accompanying drawings, which constitute part of this specification, and then more specifically defined in the claims at the end of the description.

In the accompanying drawings; wherein similar reference characters are used to designate corresponding parts throughout the several views:

Figure 1 is a perspective view showing the carrier as applied to the running board of an automobile when in use for holding luggage.

Fig. 2 is a detailed view of one pair of adjustable members of the carrier drawn to a larger scale.

Fig. 3 is a broken side view of said members to illustrate more clearly how they are adjusted and held in adjusted position, and

Fig. 4 is a section through one pair of carrier members as shown in Fig. 1.

The carrier consists of one or more pairs of adjustable members 1 and 2 adapted to stand upright at either side of the luggage. The member 1 has two parallel horizontal base pieces 3 and 4, while the member 2 has a single horizontal base piece 5 designed to be placed between the base pieces 3 and 4 of the member 1. The base pieces 3 and 5 have correspondingly spaced series of perforations 6 and 8, respectively, therein, and each of said base pieces is also provided

with a projecting lug or pin adapted to engage any one of the perforations in the other base piece. The lug or pin 7 carried by the base piece 3 projects downwardly to engage any one of the perforations 8 in the base piece 5, while the pin or lug 9 on the latter base piece extends upwardly to engage any one of the perforations 6 in the base piece 3. It will thus be seen that by placing said lugs in different ones of the perforations, the members 1 and 2 may be readily adjusted at different distances apart to fit various sizes of boxes, packages, or other luggage.

The base piece 4 on the member 1 is spaced below the perforated base piece 3 far enough to admit the running board 11 between said base piece 4 and the base piece 5 when the latter is arranged in adjusted position, as illustrated, so that said running board serves to lock the members in adjusted position. In other words, when the running board is between the base pieces 4 and 5, the latter cannot be lowered far enough to disengage the pins or lugs 7 and 9 from the perforations 6 and 8, respectively. The members of the carrier are, therefore, positively retained in adjusted position as long as they are attached to the running board, and there is no danger of the members spreading apart or slipping relative to one another even though the luggage receives heavy jolting in running over rough roads.

The carrier is fastened to the running board by set screws 10 mounted on the base piece 4 and adapted to be tightened up against the under surface of the running board. This tightening action of the set screws for clamping the carrier to the running board also presses the base pieces 5 and 3 firmly together, thereby preventing any relative vertical movement or rattling of the parts.

The members 1 and 2 have slots 12 and 13, respectively, in their upper end portions, through which straps 14 are passed for holding the luggage 15 down between said members. While two pairs of carrier members are illustrated in Fig. 1, and this number is most often used, it will be understood that a single pair or any other number of pairs may be employed according to the dimensions of the luggage to be carried.

Having thus described my invention, what I claim as new and desire to secure by Letters Patent of the United States is:

1. A luggage carrier of the character de-

scribed consisting of a pair of upright members, one having a pair of horizontal base pieces and the other having a single base piece adapted to be arranged between the base pieces of the first member, means for adjustably connecting the single base piece of the second member to the upper base piece of the first member, and means carried by the lower base piece of the first member for clamping the running board of an automobile between it and the base piece of the second member.

2. In a luggage carrier of the character described, the combination with one upright member having two horizontal base members, of a second upright member having a single horizontal base member adapted to be arranged between the base pieces of the first member, the single base piece of the second member and the upper base piece of the first member having series of perforations therein, lugs on said base pieces to engage the perforations of the other base pieces for adjustably connecting them together, and means mounted on the lower base piece of the first member for clamping the running board of an automobile between the same and the base piece of the second member and holding the lugs in the perforations in which they are arranged.

3. In a luggage carrier of the character described, the combination with one upright member having two parallel base pieces, of a second upright member having a single base piece adapted to be arranged between the base pieces of the first member, the base piece of the second member and the upper base piece of the first member having perforations therein, oppositely extending lugs on said base pieces to engage the perforations in the other base pieces for adjustably connecting the members together, and means for clamping the running board of an au-

tomobile between the lower base piece of the first member and the base piece of the second member, the spacing of the two base pieces of the first member being such that the lugs cannot be disengaged from the perforations when the running board is arranged between the lower base piece of the first member and the base piece of the second member.

4. In a luggage carrier of the character described, the combination with one upright member having two parallel base pieces, of a second upright member having a base piece adapted to be arranged between the base pieces of the first member, means for adjustably connecting the base piece of the second member to the upper base piece of the first member, and means mounted on the lower base piece of the first member for clamping an automobile running board between said lower base piece of the first member and the base piece of the second member, the running board when so arranged serving to lock the members in adjusted position.

5. In a luggage carrier of the character described, the combination with one upright member having two parallel base pieces, of a second upright member having a base piece adapted to be arranged between the base pieces of the first member, means for adjustably connecting the base piece of the second member and one of the base pieces of the first member, and means for clamping the running board of an automobile between the base piece of the second member and the other base piece of the first member, the running board when arranged between said base pieces serving to lock the members in adjusted position.

In testimony whereof I have signed my name to this specification.

GERTRUDE G. SCOTT.
